UNITED STATES PATENT OFFICE.

JOHN O. MORRIS, OF WASHINGTON, DISTRICT OF COLUMBIA, ASSIGNOR TO ECLIPSE CIGAR STEMMING MACHINERY COMPANY, A CORPORATION OF NEW JERSEY.

TOBACCO-STEMMING MACHINE.

Application filed November 19, 1924. Serial No. 750,742.

In the drawings:

Figure 1 is a front elevation of a stemming machine embodying my invention.

Figure 2 is a top plan view of Figure 1.

Figure 3 is an end elevation of Figure 1.

Figure 4 is an enlarged detail view of the knife assembly.

Figure 5 is a top plan view of Figure 4.

Figure 6 is side views of portions of toothed belts showing different formations of teeth.

Figures 7, 8 and 9 are detail views.

My invention relates to machines for stripping the stems from tobacco leaves and to straighten the leaf after it has been stemmed.

One of the objects of my invention is to provide means whereby the stripped stem may be cut from the leaf at any predetermined point in the stripping operation so that more or less of the stem may be left in the leaf as desired. Of course, when the severing means is moved to inoperative position the entire stem may be stripped from the leaf.

Another object of my invention is to provide a gripping and straightening means for the stemmed leaf adjustable relatively to the stem severing means according to the length of stem to be severed, also to provide a conveyor belt for the stemmed leaf adjustable to maintain a right angle position relatively to the gripping and straightening means; and with these and other objects in view my invention consists of the parts and combination of parts as will be more fully set forth.

The reference numeral 1 designates the main frame of the machine which may be of any suitable construction designed to carry the other parts of the structure. This frame is designed to be placed on a bench but in case it is desirable to support it from the floor legs 2 are provided which are secured by bolts 3 to the main frame.

A driving shaft 4 is suitably journalled in the frame of the machine and provided with a worm gear 5 which meshes with a worm on one end of the power shaft 6 which in turn is provided with belt pulleys 7.

An overhang table 8 is secured to the main frame 1 and further supported by a suitable bracket 9, and at the outer end of this table is mounted a driven shaft 10 upon which are keyed the belt pulleys 11 parallel to the belt pulleys 12 on shafts 4. Belts 13 are

mounted on these pulleys. A third belt 14 is mounted at one end on one of the pulleys 11 and at its other end on an idler pulley 15 which is positioned beyond the stripper rolls 16. A fourth belt 17 is also mounted on one of the pulleys 11 with its other end mounted on an idler pulley 18, the belt 17 being much shorter than the other belts, there being an abutment 19 adjacent the belt 17 against which the butts of the leaf stems are pressed when the leaf 20 is placed in the machine by the operator.

In my machine I provide two toothed edge contacting belts 21, 22, with the teeth of one belt opposed to and in register with the teeth of the other belt, as more clearly seen in Figure 6 wherein I have shown teeth of different shapes whereby round and rectangular stems may be firmly grasped and conveyed to the stripper rolls 16 as will be readily understood by those skilled in this art. These toothed belts 21, 22, are mounted on pulleys 23, 24, 25, and a pulley in alignment with pulley 25 and positioned vertically below the pulley 24 and on the same shaft 26 as pulley 24. A worm 27 is mounted on shaft 6 and engages a worm on the two pulleys on shaft 26 whereby the toothed belts are driven. It will be seen that the toothed belts 21, 22, are in edge contact.

Extending from the abutment 19 is a presser arm 28 under which the butt end of the leaf stem is pushed by the belt 17 which arm firmly presses the said butt end down between the teeth of the belt 22 as the belt is travelling around the pulley 25 whereby the butt end is propelled to the point of edge contact between the belts 21, 22, and firmly clamped between the edges of the two belts and between the teeth thereof and propelled to bring the butt end of the leaf into engagement with the stem drawing rolls 16 which pull the stem rearwardly from the stripping belts 21, 22, and the leaf is bunched on the other side of the stripping belts 21, 22, as best seen in Figure 2. The severing knife 29 is in operation and has been adjusted to sever the stem a predetermined length and in the travel of the leaf on belt 14 the stripped stem is brought into contact with the knife and severed, at which time the apex of the stemmed leaf is in a position to be drawn in between drawing rollers 30, 31, whereby the leaf is drawn from the strip-

100

ping belts and straightened. The rollers deliver the straightened leaf to the chute 32 from whence it passes to the conveyor belt 33.

The chute 32 and drawing rollers 30 and 31 are adjustably mounted on the frame of the machine by means of the pin and slot connection 34, and the conveyor belt 33 is adjustable on the frame so that it may be maintained at right angles to the chute 32. The rollers 30 and 31 are provided with intermeshing gears 35. 36 is a belt pulley secured to the main shaft 6, and 37 is a belt pulley secured to the stub shaft 38 which is mounted in a bearing 39. A universal joint 40 between the stub shaft 38 and the roller 30 transmits power from the shaft 38 to the rollers 30, the belt pulleys 37 and 36 being connected by a suitable belt 41.

The rotary knife 29 is keyed to a shaft 42 mounted in a journal bearing 43 which is carried by bracket 45 adjustably secured by means of the bolt 46 to the part 47 of the frame of the machine. The shaft 42 is provided with the belt pulley 48 which is connected by means of the belt 49 to a belt pulley 50 on the main shaft 6. When the length of the stem to be stripped from the leaf has been determined the bracket 45 is adjusted to position the knife 29 in position to sever the strip stem the desired length.

The stem drawing roller 16 mounted upon suitable shafts which are connected by means of the gears 51, 52, and 53 of the main power shaft 6.

33 A sprocket 54 is keyed to the shaft 4 and a sprocket 55 is connected to the shaft 56 of the roller 57, said sprockets being connected by means of the drive chain 58 whereby the conveyor belt 33 is operated, the other end of the conveyor belt passing over the pulley 59.

In insuring absolute alignment of the belts 21 and 22, I provide a guide 21^a having an elongated slot longitudinal thereof through which the belt 21 slides. There is a similar guide through which the belt 22 slides and as these two guides are in vertical alignment the abutting edges of the belts 21 and 22 are maintained in perfect alignment.

50 Now to insure the proper relative position of the contacting teeth of the belts 21 and 22 I provide the pulley 29' with pins 29^a three being shown for illustration, which are equidistant apart, said pins entering between and bridging the contacting teeth of the belts 21 and 22 whereby the registry of the teeth is maintained thus insuring space between them for the butt ends of the leaf.

As will be seen in Figure 9, the rolls 32' and 33' for the bands 21 and 22 are of different width, the roll 33' being narrower than the roll 32' which results in the band 22 overlapping the roll 32'. This brings the line of contact between the teeth of the bands 21 and 22 on the periphery of the roll

32' and I have positioned pins 34' on the periphery of the roll 32' which are adapted to seat in the space between the teeth of the bands 21 and 22 whereby the teeth of the respective bands are always maintained in perfect registry. Now in case I desire to employ bands 21 and 22 with different shaped teeth all that is necessary is to remove the roll 32' and substitute another roll having the pins 34' to correspond with the perimeter of the space between the teeth of respective bands.

What I claim is:

1. A tobacco stemming machine including stripping rolls, rolls adjustably mounted relatively to the stripping rolls, said adjustable rolls being adapted to remove the stripped leaf from the stripping rolls and straighten the leaf, and a chute carried by said adjustable rolls, and a leaf conveyor belt adjustable to maintain a right angle position relative to said chute.

2. In a tobacco stemming machine, a plurality of leaf propelling belts of varying lengths, stripping rolls, opposed toothed belts, the lowermost one of which is longer than the other, between the teeth of which the leaf stem is fed, the teeth of both belts registering and firmly holding said stem and conveying the leaf to the stripping rolls, means adjacent the stripping rolls to sever the stripped stem any predetermined length.

3. In a tobacco stemming machine, a plurality of leaf propelling belts of varying lengths, stripping rolls, opposed toothed belts, the lowermost one of which is longer than the other, between the teeth of which the leaf stem is fed, the teeth of both belts registering and firmly holding said stem and conveying the leaf to the stripping rolls, means adjacent the stripping rolls to sever the stripped stem any predetermined length, leaf pulling and straightening means adjustable relatively to the stem severing means.

4. In a tobacco stemming machine, a plurality of leaf propelling belts of varying lengths, stripping rolls, opposed toothed belts, the lowermost one of which is longer than the other, between the teeth of which the leaf stem is fed, the teeth of both belts registering and firmly holding said stem and conveying the leaf to the stripping rolls, means adjacent the stripping rolls to sever the stripped stem any predetermined length, leaf pulling and straightening means adjustable relatively to the stem severing means, and stemmed leaf conveyor adjustable to maintain a position at right angles to the pulling and straightening means.

5. In a tobacco stemming machine, leaf stripping means including a pair of edge contacting belts for confining the butt of the leaf stem therebetween, stem drawing means and stem severing means at one side thereof for engaging the butt end of the leaf

stem and for severing the stem a predetermined length, a leaf pulling means at the other side for engaging the apex of the leaf.

6. In a tobacco stemming machine, leaf stripping means including a pair of edge contacting belts for confining the butt of the leaf stem therebetween, stem drawing means for engaging the butt end of the leaf stem and adjustable stem severing means at one side of said butt engaging means for severing the stem a predetermined length, a leaf pulling means at the other side for engaging the apex of the leaf.

7. In a tobacco stemming machine, leaf stripping means including a pair of edge contacting belts for confining the butt of the leaf stem therebetween, stem drawing means for engaging the butt end of the leaf stem and adjustable stem severing means at one side of said butt engaging means for severing the stem a predetermined length, an ad-

justable leaf pulling means at the other side for engaging the apex of the leaf.

8. In a tobacco stemming machine, leaf stripping means including a pair of edge 25 contacting belts for confining the butt of the leaf stem therebetween, pulleys for said belts, means on some of said pulleys to engage the belts between the teeth thereof and bridge the joint between the contacting belts, 30 whereby the teeth of the belts are maintained in registry.

9. In a tobacco stemming machine, leaf stripping means including a pair of edge 35 contacting belts for confining the butt of the leaf stem therebetween, pulleys for said belts, pins projecting from the periphery of said belts and adapted to enter the spaces between the teeth of said belts to maintain the teeth in registry.

In testimony whereof I affix my signature.
JOHN O. MORRIS.
